UNITED STATES PATENT OFFICE.

CHARLES A. CARSCADIN AND GEORGE A. WOODMAN, OF CHICAGO, ILLINOIS, ASSIGNEES,
BY MESNE ASSIGNMENTS, TO AMERICAN STEEL FOUNDRIES, OF CHICAGO, ILLINOIS,
A CORPORATION OF NEW JERSEY.

DRAFT-GEAR.

1,287,633.

Specification of Letters Patent. Patented Dec. 17, 1918.

Application filed May 28, 1915. Serial No. 30,901.

To all whom it may concern:

Be it known that we, CHARLES A. CARSCADIN and GEORGE A. WOODMAN, citizens of the United States, both residing at Chicago, in the county of Cook and State of Illinois, have jointly invented certain new and useful Improvements in Draft-Gears, of which the following is a specification.

This invention relates in general to draft gears and more particularly to that type of draft gears in which tandem springs are employed, both of which are utilized in independently transferring the pulling and buffing forces from the draw-bar to the draft arms.

It is an object of our invention to provide means employing a minimum number of relatively simple and inexpensive parts for transferring the forces applied to the draw-bar directly to a plurality of springs arranged in tandem and thence to the draft arms at a plurality of points.

A further object of our invention is to provide a draft gear in which rigid connections between the butt of the draw-bar and the yoke are eliminated and whereby pulling and buffing forces are transferred from the draw-bar to the draft arms simultaneously at a plurality of points.

A still further object of our invention is the provision of means whereby buffing forces are transferred from the draw-bar to the draft arms without subjecting the yoke to the stresses thereof.

Other objects and advantages of the invention will be apparent as it is better understood by reference to the following specification when read in connection with the accompanying drawing in which—

Figure 1 is a side elevation, partially in section, of a draft gear according to our invention;

Fig. 2 is a plan view of the underside thereof;

Fig. 3 is a side elevation similar to Fig. 1 of a slightly different form of the invention;

Fig. 4 is a vertical section on the line 4—4 of Fig. 3, and

Figs. 5, 6 and 7 are side elevations partially in section showing slightly different forms of our invention.

Referring to Figs. 1 and 2 of the drawings, 1 indicates a draw-bar provided with a

butt 2, which is adapted to be embraced by the end of the yoke 3 and held from movement in one direction longitudinally thereof by the flanges 4 at the forward end of the yoke 3. The butt 2 is prevented from side-wise displacement by an integral portion 5 at one side of the yoke and by a removable member 6 at the other side thereof adapted to be held in position on the yoke 3 by a bolt 7 disposed through said member and through a lug 8 integral with the yoke 3.

Mounted in the yoke 3 are two pairs of follower plates 9 and 10, plates 9 being adapted to movement in either direction longitudinally with respect to the yoke 3 and plates 10, being prevented from movement in one direction longitudinally of the yoke 3 by the end 11 thereof and the lugs 12 integral therewith midway of the length of the yoke.

Springs 13 and 14 are disposed between each pair of follower plates 9 and 10, it being understood that while two springs are shown, one within the other, one of these springs may be omitted, if desired. A rod 15 extends between the freely movable follower plates 9, passing through an opening 16 in the foremost follower plate 10. The rod 15 is adapted to transfer forces directly between the follower plates 9.

Disposed on either side of the yoke 3, and secured in any suitable manner to the body of the car, are the draft arms 17 provided with oppositely disposed lugs 18 forming shoulders, against which the follower plates 9 and 10 rest, and adapted to prevent movement of each of the follower plates in one direction longitudinally of the draft arms. From an examination of Fig. 2 of the drawings it will be readily understood that the follower plates 9 are prevented from forward movement while the follower plates 10 are prevented from rearward movement by these shoulders.

It is believed that the operation of my device will be readily apparent without further description of the structure thereof. When pulling forces are exerted on the draw-bar 1 the yoke 3 will be drawn forwardly carrying with it the follower plates 10 to compress the springs 13 and 14 between the follower plates 10 and the follower plates 9, which are held from forward movement by the shoulders on the draft arms 17. Upon the appli-

cation of buffing forces to the draw-bar 1, the butt 2 thereof will move rearwardly in the yoke, carrying with it the follower plates 9, the rearmost follower plate 9 being actuated 5 through the rod 15. The springs 13 and 14 will be compressed between the plates 9 and 10, the latter being held from rearward movement by the shoulders on the draft arms 17. In either case the forces are transferred 10 from the draw-bar through the springs, independently, to the draft arms at a plurality of points and it will be readily understood that buffing forces, which are most severe, are transferred to the draft 15 arms without subjecting the yoke to the stress of such forces.

Referring to Figs. 3 and 4 of the drawings, the structure of this form of my invention is identical with that previously described, 20 except that the follower plate 10' is formed integral with the yoke 3, as best shown in Fig. 4. The operation of the device is identical with that of the form of invention shown in Figs. 1 and 2.

25 In Figs. 5 and 6 two forms of the invention are shown in each of which the rod 15' is made integral with the follower plate 9' and in Fig. 6 the rod 15' extends through an opening in the foremost follower plate 30 9'' to engage directly with the butt 2 of the draw-bar. The follower plate 10 in Fig. 5 is as shown in Fig. 1, while the follower plate 10' in Fig. 6 is made integral with the yoke 3, as in Figs. 3 and 4. The structure 35 is otherwise identical and the operation of these two forms of our invention does not differ from that described in connection with Figs. 1 and 2.

In Fig. 7 we disclose a form of our invention 40 in which the rod 15'' is formed integral with the foremost coupler plate 9 and in which the rearmost follower plate 9 is provided with a rod 19 extending rearwardly through the rearmost follower plate 10'' and 45 through the end 11 of the yoke 3. The operation of this form of our invention is identical with that described in connection with Figs. 1 and 2, the rod 19 acting merely as a means for retaining the rearmost follower 50 plate 9 in proper alignment in the yoke.

It will be apparent that various changes may be made in the form, construction and arrangement of the parts without departing from the spirit and scope of the invention 55 or sacrificing any of its material advantages, the forms hereinbefore disclosed being merely preferred embodiments thereof.

I claim:

1. In a device of the class described, the 60 combination of a yoke, a draw bar shank embraced by and having a keyless connection with said yoke and adapted for longitudinal movement with respect thereto, a plurality of sets of followers, springs disposed between said followers, and means connecting

the front followers of the first and second sets whereby buffing forces are applied directly to the several sets of followers by the action of the shank against the front follower of the first set without movement of 70 the yoke.

2. A draft rigging comprising in combination a yoke, a draw-bar having a shank embraced by and having a keyless connection with said yoke, a plurality of sets of 75 followers, springs between the followers, draft arms adapted to be engaged by said followers and to limit the extent of bodily movement thereof, means connecting the front followers whereby the buffing forces 80 are transmitted from the front follower of the first set to the front follower of the second set thereby equally distributing the buffing shocks to the several sets of springs and through them to the draft arms at a 85 plurality of points.

3. A draft gear of the class described, in combination a yoke, a draw-bar having a butt engaged by and having a keyless connection with said yoke, a plurality of sets of 90 followers, the butt and yoke being removably connected by a strap whereby the shank is longitudinally movable in said yoke under buff, means associated with said yoke for positively moving the rear followers of each 95 set therewith, means associated with the front followers of each set whereby said followers are simultaneously moved toward the rear followers when the shank is moved rearwardly in said yoke under buff against 100 the first follower of the first set.

4. A draft gear of the class described, comprising in combination a shank, a yoke having a keyless sliding connection with respect to said shank, a plurality of sets of 105 followers one follower of each set being movable with the yoke, one follower of each set being movable in both directions with respect to the yoke, means associated with the front followers of the several sets whereby motion is imparted thereto by the shank being moved rearwardly in the yoke under buff transferring to the other followers the buffing forces delivered to the front follower 110 of the first set by said moving followers 115 through said springs.

5. In a device of the class described, the combination of a yoke, a draw-bar having a keyless connection with said yoke, the butt engaging one end of said yoke and adapted 120 for longitudinal movement with respect thereto, a plurality of sets of followers, one follower of each set being freely movable in both directions longitudinally with respect to said yoke, the other follower of each set 125 being movable only with the yoke, springs disposed between said followers, draft arms having oppositely disposed lugs adapted to be engaged by the respective followers, and to limit the lateral movement thereof longi- 130

tudinally in said draft arms whereby force applied to said draw-bar is simultaneously transferred to said draft arms at a plurality of points, and a rod connecting the front followers of the first and second sets whereby

5 buffering forces applied to the front follower of the first set are transferred to the second

set and the strains thereof transferred to the draft arms without movement of the yoke.

CHARLES A. CARSCADIN.
